ABSTRACT OF THE DISCLOSURE

A dryness control for a laundry machine which results in safe and consistent performance regardless of grounding of the machine, the way the plug of the service cord is inserted in an electrical outlet or the existence of exposed metal parts in the dryer drum. An electrical resistance is connected between one of the power input leads and a moisture sensing electrode which senses dryness of the fabric within the dryer.

BACKGROUND OF THE INVENTION

Field of the invention

The invention relates in general to dryer apparatus and more specifically to control circuitry for dryness controls in fabric dryers.

Description of the prior art

The prior art in regard to which the present invention is an improvement is exemplified by the pending application of the assignee of the present application, namely, U.S. Ser. No. 548,678, filed May 9, 1966, wherein is disclosed a dryer having electrodes for sensing the predetermined degree of dryness of the fabrics in the treatment zone of the machine.

SUMMARY OF THE INVENTION

The present invention relates to a circuit for a fabric dryer laundry machine having moisture sensing electrodes and a timer motor to which electrical power is connected by at least a pair of input leads. A resistor is connected in circuit with one of the input power terminals and the chassis and one terminal of the moisture sensing electrodes is connected to the chassis. The control circuit assures safe operating conditions of the dryer, even if the machine is not grounded by a grounding conductor. The circuit also provides safe operating conditions for either way in which the power plug is inserted into the electrical outlet and also provides safe operating conditions if metal parts of the dryer become exposed.

Other objects, features and advantages of the present invention will be readily apparent from the following detailed description of certain preferred embodiments thereof taken in conjunction with the accompanying drawings.

BRIEF DESCRIPTION OF THE DRAWINGS

FIG. 1 illustrates the control circuit of this invention schematically with the cabinet of the dryer properly grounded and the neutral power line connected to the timer motor;

FIG. 2 illustrates the control circuit of this invention with the neutral power line connected to the timer motor and the cabinet of the dryer not grounded;

FIG. 3 is a schematic view with the ungrounded power line connected to the timer motor and with the cabinet of the dryer grounded;

FIG. 4 illustrates the control circuit with the ungrounded power line connected to the timer and motor and the cabinet of the dryer not grounded; and

FIG. 5 illustrates a stationary bulkhead of a dryer

2

illustrating the moisture sensing electrodes of the dryer.

DESCRIPTION OF THE PREFERRED EMBODIMENTS

5 Although the present invention is generally applicable to dryers, an illustrative embodiment of a typical dryer in which the inventive subject matter would have application is shown in FIG. 5 which shows electrodes 11 and 12 of a sensor assembly 13. The electrodes 11 and 12, respectively, comprise a plurality of elongated fingers 11a and 12a. An air blower (not shown) provides air to the dryer through the inlet supply opening 14 and after the air is passed through the fabric to dry it, it passes out the outlet opening 16.

10 The dryness control of this invention is illustrated in FIGS. 1 through 4. The circuit diagrams of all of the figures are similar and they differ only in the grounding connections and in the way the neutral and hot power lines have been connected to the dryer. For example, in

15 each of the schematic diagrams, timer motor 17 is illustrated and a silicon control rectifier 18 is connected in parallel with the motor 17. The gate electrode 19 of the silicon control rectifier 18 is connected to a neon lamp 21 which has its opposite side connected to a resistor R₃. The other side of resistor R₃ is connected to the cathode of a diode 22. The anode of diode 22 is connected to a resistor R₅ which has its other side connected to moisture sensing electrode 11. The moisture sensing electrode 12 is grounded to the chassis of the machine.

20 The capacitor C₁ has one side connected to the anode of diode 22 and the other side connected to an input lead 23 of the control circuit. A resistor R₆ is connected between leads 23 and the chassis of the machine. The other input lead 24 is connected to a timer contact switch 26 which is connected in circuit with the series resistor R₁.

25 The other side of the resistor R₁ is connected to the second terminal of the timer motor 17 and to the cathode of the silicon controlled rectifier 18. A resistor R₂ is connected between the gate 19 and the cathode of the silicon controlled rectifier 18. A resistor R₄ is connected from the cathode of the diode 22 to the cathode of silicon controlled rectifier 18.

30 All of the portions of the control circuit illustrated in FIGS. 1 through 4 up to this point are the same. The input leads 23 and 24 are connected to an electrical plug which is inserted into a suitable power socket during operation of the machine. The plug to which lines 23 and 24 are connected may be inserted into the socket such that line 23 is connected to the neutral line of the power socket and the line 24 is connected to the ungrounded power lead. Alternatively, the plug to which lines 23 and 24 are connected may be inserted into the power socket such that the line 23 is connected to the ungrounded power line L₁ and the lead 24 is connected to the grounded neutral lead of the power supply. Dryers should be grounded by a grounding conductor which extends from the chassis of the dryer to a suitable ground point as for example a water pipe. FIGS. 1 through 4 illustrate the control circuit connected to the power lines in various ways and with grounded and ungrounded conditions.

35 FIG. 1, for example, illustrates the input lead 23 connected to the neutral power line N and point Y and with a grounding connector connected from the chassis of the machine to an earth ground which is also connected to the neutral power line N. This is the recommended desired installation and the dryer cabinet will act as a conductor making connections which short out the resistor R₆. When the neutral line N is positive, the capacitor C₁ will charge through timer switch 26, resistors R₁ and R₄ and rectifier diode 22. When wet fabric contacts sensors 11 and 12, the DC voltage developed on capacitor C₁ will be quite small and therefore the voltage between points

40 45 50 55 60 65 70

C and D will reach the breakdown voltage of neon 21. Neon 21 will fire and turn on the SCR 18 and timer motor 17 will be shunted by a short circuit during half the time. Timer motor 17 may be a shaded pole motor which will not operate on half-wave voltage and thus the timer motor 17 will not advance when wet fabric bridges the sensor. As the fabric in the dryer becomes drier and presents a higher resistance across the sensors 11 and 12, the voltage on capacitor C₁ will increase. When this voltage becomes so high that the voltage from point C to point D is insufficient to fire the neon 21, the timer motor 17 will begin to operate and run out to terminate the dryer cycle.

The resistor R₅ is selected large enough to limit the current to protect a person touching sensors 13 from shock hazard. Resistors R₁, R₄ and R₅ and capacitor C₁ are selected so that the difference between the peak of the AC line voltage minus the DC voltage across the capacitor C₁ will exceed the ionization voltage of the neon 21 over the full design range of the line voltage supplied to the machine.

FIG. 2 illustrates the supply lead 23 connected to the neutral line N of the power supply and the input lead 24 of the machine connected to the ungrounded supply of the power supply L₁. However, in this figure a ground lead has not been connected from the chassis of the machine to a suitable earth ground. Under these conditions the circuit of FIG. 2 operates the same as that of FIG. 1 except that the resistor R₆ has been placed in series with the sensor 13. This causes the DC level on the capacitor C₁ to be somewhat higher than in the circuit of FIG. 1. Alternatively, the required supply line voltage connected to leads N and L₁ will need to be slightly higher than for the configuration shown in FIG. 1 to obtain the same operating conditions.

FIG. 3 illustrates the condition wherein input lead 24 has been connected to the neutral power lead and input lead 23 has been connected to the ungrounded lead L₁. The chassis of the machine has been connected to an earth ground by suitable grounding conductor 27. In this situation the capacitor C₁, resistor R₅ and sensor 13 are connected in series across the line terminals N and L₁. The capacitor C₁ is selected so that its 60 cycle impedance will be low with respect to resistor R₅ and this causes nearly full line voltage to appear between points C and D when wet fabric bridges sensors 13. Therefore, when L₁ is positive the neon 21 will fire and the timer motor 17 will not operate. As the clothes become dry and present a higher resistance to sensor 13, capacitor C₁ will charge through switch 26, resistors R₁ and R₄ and the diode rectifier 22. When this voltage becomes so high that the voltage from point C to point D is insufficient to fire the neon 21, the timer motor 17 will begin to operate and run out to terminate the dryer cycle.

FIG. 4 is very similar to FIG. 3 except the grounding conductor 27 has not been connected. This circuit operates substantially the same as the circuit of FIG. 2. The control circuit of this invention eliminates possible shock hazard for both conditions of the power plug and also provides protection even if the ground lead is not connected. R₆ is selected large enough so that when wet clothes bridge sensors 13 the current through the parallel combination of R₅ and R₆ is limited to protect a person touching sensors 13 from shock hazard. Thus, the problem of possible shock hazard at the exposed electrode is overcome and, consistent performance is achieved re-

gardless of machine grounding and of reversed line plug insertion.

If "floating" electrodes are used, such grounding paths may affect the performance of a dryer. In accordance with the present invention a sensor is used which has one electrode connected to chassis ground. Grounded structural parts therefore act as extensions of the sensor and therefore have little or no affect on drying performance.

Although minor modifications might be suggested by those versed in the art, it should be understood that I wish to embody within the scope of the patent warranted hereon all such modifications as reasonably and properly come within the scope of my contribution to the art.

The embodiments of the invention in which an exclusive property or privilege is claimed are defined as follows:

1. In a clothes dryer having a chassis, a control circuit having a timer motor connected between a pair of input power leads, a controlled conduction device having a control terminal connected in circuit with said timer motor to render said timer motor inoperative when said controlled conduction device is in one conduction state, a gating circuit for said controlled conduction device including a capacitor and a plurality of moisture sensing electrodes, the improvement comprising connecting said capacitor in series with a diode between one of said pair of input power leads and said control terminal, connecting a first resistance between said control terminal and the other of said pair of input power leads, connecting said plurality of moisture sensing electrodes between said control terminal and said chassis with one of said electrodes connected to said chassis, and connecting a second resistor between said one of said pair of input power leads and said chassis.

2. A control circuit according to claim 1 wherein said controlled conduction device is connected in parallel with said timer motor.

3. A control circuit according to claim 2 wherein said controlled conduction device is a silicon controlled rectifier.

4. A control circuit according to claim 2 comprising connecting a third resistor in series with said timer motor between the input power leads, and connecting a fourth resistor between said plurality of moisture sensing electrodes and said control terminal.

5. A control circuit according to claim 4 comprising connecting a fifth resistor in series with a neon gate between said diode and said control terminal, and connecting a sixth resistor between said control terminal and the connection of said first resistance and the other of said input power leads.

6. A control circuit according to claim 5 wherein said controlled conduction device is a silicon controlled rectifier and said control terminal is the gate electrode.
